UNITED STATES PATENT OFFICE.

ABRAHAM DVILNSKY, OF BROCKTON, MASSACHUSETTS.

WELTED SHOE AND WELT THEREFOR.

Application filed May 5, 1926. Serial No. 106,801.

The object of this invention is to provide a welted shoe bottom with an exposed edge of greater thickness than the combined thickness of the usual welt and the outsole, without the expense attending the employment of the middle sole heretofore used.

I attain this object by securing to the usual welt before it is incorporated in the shoe, a thickening strip which is narrower than the welt, thickens the outseam receiving outer edge portion of the welt without thickening the inner edge portion thereof, so that the thickening strip is wholly outside the inseam stitches, thickens the shoe bottom at its exposed marginal portion only, and is adapted to receive the usual outseam stitches.

Of the accompanying drawings forming a part of this specification,—

Figure 1 shows in perspective a portion of a welt provided with a thickening strip in accordance with my invention.

Figure 2 is a fragmentary sectional view, showing portions of the insole, upper, and welt of a welted shoe, together with the thickening strip, in the relative positions these parts occupy during the operation of forming the inseam stitches, and showing also a portion of the curved welt sewing-machine needle, inserted in the welt, upper, and insole, without entering the thickening strip.

Figure 3 is a fragmentary sectional view, showing the welt united by inseam stitches, to the upper and insole, and the outsole united by outseam stitches to the welt and thickening strip.

The drawings are on an enlarged scale.

The same reference characters indicate the same parts in all of the figures.

In the drawings, 12 designates a welt of ordinary form, having the usual stitch-receiving groove 13, in the inner edge portion of its inner face. The welt is united to the lip 14 of the insole 15, and to the edge portion of the upper 16, in the usual way, by inseam stitches 17, formed by the curved needle 18 of a Goodyear or other welt sewing-machine.

My invention is characterized by a thickening strip 19 attached, preferably by cement, to the inner side of the welt. The strip is narrower than the welt, its outer edge being flush with the outer edge of the welt, and its inner edge 20 being bevelled and offset outward from the inner edge of

the welt, and from the inseam stitch-receiving groove 13.

The arrangement is such that during the operation of securing the welt to the upper and insole, the bevelled edge 20 clears, or is out of the path of the needle 18, as shown by Figure 2, so that the thickening strip is wholly outside the inseam stitches 17, as shown by Figure 3. The strip includes a portion of uniform width between the outer and inner edges. Said portion bears on the marginal portion of the inner face of the outsole 23, and is united, with the welt, to the outsole by the usual outseam stitches 21. The strip surrounds the layer 22 of bottom filler between the outer and inner soles and thickens the shoe bottom at its exposed marginal portion only, so that the shoe bottom is thickened at less expense than by the usual middle sole, coextensive with the outer sole. The strip 19 is attached to the welt before the incorporation of the latter in the shoe, and is incorporated with the welt, and not by a separate operation.

The filling strip may be of any suitable flexible material, as leather or rubber.

I claim:

1. A shoe welt having an inseam stitch-engaging inner edge portion, an outseam stitch-engaging outer edge portion, and a thickening strip secured to the inner face of the welt flush with the outer edge of the latter, the thickening strip being narrower than the welt, so that the strip is wholly outside the inseam stitch-engaging portion of the welt, said strip having an outseam stitch-engaging portion bearing on the outseam stitch-engaging portion of the welt, and an inner edge formed to clear the path of a curved needle.

2. A shoe welt having a stitch-receiving groove at the inner edge portion of its inner face, and a thickening strip secured to said inner face, and flush at its outer edge with the outer edge of the welt, the thickening strip being narrower than the welt, so that it is wholly outside the stitch-receiving groove, the inner edge of the thickening strip being bevelled, to clear the path of a curved inseam stitch-forming needle, and including a portion of uniform thickness between the outer and inner edges, adapted to receive outseam stitches engaged with the welt.

In testimony whereof I have affixed my signature.

ABRAHAM DVILNSKY.
